UNITED STATES PATENT OFFICE

169,234

SHOWER DOOR FRAME

John A. Woodworth, Los Angeles, Calif.

Application August 27, 1952, Serial No. 21,201

Term of patent 14 years

(Cl. D13—1)

To all whom it may concern:

Be it known that I, John A. Woodworth, a citizen of the United States of America and residing at Los Angeles, in the county of Los Angeles, State of California, have invented a new, original, and ornamental Design for a Shower Door Frame, of which the following is a specification, reference being had to the accompanying drawing, forming part thereof, in which:

Fig. 1 is a perspective view of a shower door frame, showing my new design; and

Fig. 2 is an enlarged sectional and perspective view showing a portion of the frame as indicated by the line 2—2 of Fig. 1.

The rear of the frame is plain in appearance.

I claim:

The ornamental design for a shower door frame, substantially as shown and described.

JOHN A. WOODWORTH.
